DESIGN.

J. HARTLEY.

UPHOLSTERY FABRIC.

No. 15,509.

Patented Nov. 4, 1884.

UNITED STATES PATENT OFFICE.

JOHN HARTLEY, OF PHILADELPHIA, PENNSYLVANIA, ASSIGNEE TO WILLIAM HUNTER & SON, OF SAME PLACE.

DESIGN FOR AN UPHOLSTERY FABRIC.

SPECIFICATION forming part of Design No. 15,509, dated November 4, 1884.

Application filed August 12, 1884. Term of patent 15 years.

To all whom it may concern:

Be it known that I, JOHN HARTLEY, a subject of the Queen of Great Britain, residing at Philadelphia, in the county of Philadelphia and State of Pennsylvania, have invented and produced a new and original Design for an Upholstery Tapestry or Damask Fabric, in such shades as may be desired; and I do hereby declare that the photographic print accompanying this specification conveys to any one skilled in the art a clear understanding of the same, and is sufficient to enable such person to use my invention.

What I claim as my invention, and desire to secure by Letters Patent, is—

The design for an upholstery tapestry or damask fabric, as shown in the photographic print accompanying this specification.

JOHN HARTLEY.
